DESIGN FOR A CARTON

Jacob Cohen, Forest Hills Township, Nassau County, N. Y., assignor to Laurel Intimates, Inc., a corporation of New York

Application July 30, 1947, Serial No. 140,613

Term of patent 3½ years

(Cl. D80—5)

To all whom it may concern:

Be it known that I, Jacob Cohen, a citizen of the United States of America and a resident of the township of Forest Hills, in the county of Nassau and State of New York, have invented a new, original, and ornamental Design for a Carton, of which the following is a specification, reference being had to the accompanying drawing, forming a part thereof.

Fig. 1 is a front view of a carton showing my new design, and

Fig. 2 is a rear view thereof.

The girdle portion shown on the figure on the front of the carton constitutes a window.

I claim:

The ornamental design for a carton, substantially as shown and described.

JACOB COHEN.
